DISPENSING CONTAINER FOR ROLLED SHEET MATERIAL

Eugene Kawecki, Detroit, Mich., assignor to
 K & L Plastic Products Inc., St. Clair Shores,
 Mich., a corporation of Michigan

Application November 13, 1950, Serial No. 195,296

5 Claims. (Cl. 312—39)

1

This invention relates to a dispensing container for rolled sheet material such, for example, as wax paper and aluminum foil.

It is an object of this invention to produce a dispensing container for rolled sheet material which is of simple structure, efficient in operation, and easily loaded and unloaded without movement of any part of the container.

This invention also contemplates a dispenser for rolled sheet material which can be readily molded of plastic material in one operation as an integral unit.

In the drawings:

Fig. 1 is a perspective view of the dispenser for rolled sheet material which is the subject of this invention.

Fig. 2 is a front elevation of the dispenser showing the same loaded with a roll of sheet material.

Fig. 3 is a front elevation of the dispenser showing the same in the process of being loaded with a roll of sheet material.

Fig. 4 is a bottom plan view of the dispenser.

Fig. 5 is an end elevation of the dispenser.

Fig. 6 is a section along the line 6—6 of Fig. 2.

Fig. 7 is a rear elevation of the dispenser.

Fig. 8 is a sectional view corresponding to Fig. 6 but showing a modified form of the dispenser.

The instant dispenser comprises a top wall 1, front wall 2, end walls 3 and 4, flange or ledge 5 extending inwardly from the lower edge 6 of end wall 3, flange or ledge 7 extending inwardly from the lower edge 8 of end wall 4, and vertical rib 9 extending upwardly from the upper face of flange 7. Rib 9 is positioned parallel to end wall 4 and between the inner edge 10 of flange 7 and end wall 4. Rib 9 is spaced inwardly from end wall 4 and extends from the front wall 2 rearwardly to a point 11 just short of the rear edge 12 of flange 7. Top wall 1 extends forwardly and downwardly from its rear edge 13 and merges with front wall 2. Rear edge 12 of flange 7, rear edge 14 of flange 5, and rear edges 15 and 16 of end walls 3 and 4, respectively, are all located in the same vertical plane.

Ears 17 extend outwardly from the rear edges 15 and 16 of end walls 3 and 4. The dispenser is secured to a vertical wall or support 18 by passing screws 19 through openings 20 in ears 17. When the dispenser is thus secured upon a vertical wall 18, edges 12, 13, 14, 15 and 16 contact the vertical surface 21 of such wall. It will be noted that flanges 5 and 7 are flat or planar and slope or are inclined slightly downwardly from rear edges 12 and 14. In other words, flanges 5 and 7, which serve as supports or shelves for the roll of web material 25, are inclined downwardly toward the front wall 2. Thus, the angle B between the upper surfaces of flanges 5 and 7 and the vertical plane which runs through the rear edges 12, 13, 14, 15 and 16 is slightly greater than a right angle, for example, about 92°. The slope of flanges 5 and 7 is sufficient so that the

2

roll 25 will roll down and contact the inside face of front wall 2. The lower horizontal edge 26 of front wall 2 is serrated. The lower portion of front wall 2 beneath curve section 27 is planar and makes an angle A slightly greater than 90° with a line 28 perpendicular to face 21 of support 18.

Referring to Figs. 4, 5 and 7, it will be noted that the forward edge 29 of flange 7 and the forward edge 30 of flange 5 are positioned rearwardly of serrated edge 26 so that the web of sheet material 31 forming roll 25 passes downwardly in back of serrated edge 26 and forwardly of edges 29 and 30.

Figs. 2 and 3 illustrate how the roll 25 is loaded into the dispenser. The axial extent or length of roll 25 is greater than the distance between the inner edge 10 of flange 7 and the inner edge 32 of flange 5 but less than the distance between rib 9 and end wall 3. The distance between the inner edge 32 of flange 5 and end wall 4 is sufficient so that when roll 25 is inserted into the dispenser through the opening between flanges 5 and 7 and the roll shifted to the right, Fig. 3, until one end of the roll is over rib 9 and in contact with the inner face of end wall 4, then the other end 34 of the roll will clear the inner edge 32 of flange 5, Fig. 3, and permit the roll to be moved upwardly into the container and then shifted to the left, Fig. 3, until end 34 of roll 25 rests upon flange 5 and the other end 35 of the roll rests upon flange 7 to the left of rib 9.

To remove the roll 25 from the dispenser it is only necessary to raise end 35 of the roll above the upper edge of rib 9 and then shift the roll to the right until end 34 clears edge 32 of flange 5, Fig. 3, whereupon the roll can be swung downwardly and outwardly from the dispenser.

The distance between end walls 3 and 4 is not critical. The important thing is that wall 4 should be positioned to the right of rib 9 a sufficient distance so that the end 34 of the roll will clear edge 32 of flange 5 when the end 35 of the roll is positioned into the dispenser, as shown in Fig. 3. As a matter of economy in materials, the distance between the inner edge 32 of flange 5 and wall 4 will be about, or slightly greater than, the length of roll 25 and the distance between end wall 3 and rib 9 will be slightly greater than the length of roll 25. In actual practice the distance between rib 9 and end wall 3 is about a quarter of an inch greater than the length of roll 25.

Wall 18, Figs. 1, 4 and 6, is a vertical wall. If desired, the instant dispenser may be mounted upon a horizontal wall 40, Fig. 8. In such case rib 9 is provided with an extension 41 which extends along the inner face of wall 2 and in the plane of rib 9. When the dispenser is mounted, as shown in Fig. 8, roll 25 will rest upon the inner face of wall 2 which is inclined.

downwardly or to the right, Fig. 8 (angle A being slightly greater than a right angle), so that the roll is maintained forwardly and in contact with flanges 5 and 7 which now be positioned substantially vertically. Roll 25 will again be positioned between rib 9, 41 and the end wall 3 of the dispenser.

The instant dispenser is preferably injection molded as an integral unit from a known thermoplastic material. Owing to its integral and simple construction, the instant dispenser can be injection molded in a single shot by conventional injection molding methods.

The rib 9 cooperates with the end wall 3 and the downwardly inclined flanges 5 and 7 to present the free end 31 of the sheet material to the serrated cutting edge 26. The rib 9 cooperates with end wall 3 to determine the longitudinal position of roll 25. In loading the dispenser the space between rib 9 and wall 4 makes it possible to load the roll in the dispenser without removing any part of the integral dispenser. With the instant dispenser there is no need to remove covers, spring loaded devices, or any other part of the holder in order to load or unload the same.

In a dispenser for rolled sheet material, such as paper or aluminum foil, it is highly desirable that the overall dimensions of the dispenser should be kept to a minimum. From the above description it is evident that the instant dispenser can hold a roll of sheet material to be dispensed where the original diameter of the roll is substantially equal to the distance between the inner face of the front wall 2 and the surface 21 upon which the dispenser is mounted and wherein the overall height of the dispenser is only slightly greater than the original diameter of the roll. This object of maintaining the dispenser compact so that it is only slightly larger than the initial size of the roll of sheet material to be dispensed is made possible by the provision of locating medium or rib 9 and the provision of the space between rib 9 and the end wall 4 which, as above described, permits the loading of such a compact dispenser.

I claim:

1. A dispenser adapted for dispensing a roll of sheet material comprising a front wall, end walls, ledges located inwardly of the end walls and adapted to support the said roll adjacent its opposite ends, the ledges and lower edge of the front wall defining an opening through which said roll can be loaded into said dispenser, said ledges being spaced from the front wall to permit the passage of the sheet material between the ledges and the said front wall, a locating member positioned within the dispenser between the inner edge of one of said ledges and the adjacent end wall, said locating member being spaced inwardly from its adjacent wall and adapted to cooperate with an end of said roll for maintaining said roll upon said ledges whereby in loading said dispenser an end of the roll can be passed over said locating member into the space between said locating member and the adjacent end wall so that the other end of the roll clears the edge of the opposite ledge preparatory to shifting the roll in the opposite direction to its final dispensing position upon said ledges.

2. The dispenser defined in claim 1 wherein the ledges are inclined downwardly toward the lower edge of said front wall.

3. The dispenser claimed in claim 1 wherein the dispenser when considered as mounted with its front wall forming the bottom of the dispenser upon which the roll is supported, then said front wall is inclined downwardly toward said ledges to hold said roll in contact with said ledges.

4. A dispenser adapted for dispensing a roll of sheet material comprising a front wall, end walls, flanges extending inwardly from the end walls and adapted to support the said roll adjacent its opposite ends, the flanges and lower edge of the front wall defining an opening through which said roll can be loaded into said dispenser, said flanges being spaced from the front wall to permit the passage of the free end of the sheet between the flanges and the said front wall, a locating member positioned above one of said flanges and between the inner edge of said flange and the adjacent end wall, said locating member being adapted to cooperate with an end of said roll for maintaining said roll upon said flanges, the distance between the end wall adjacent the said locating member and the inner edge of the remote flange being greater than the distance between the inner edges of said flanges whereby a roll having a greater length than the distance between the inner edges of said flanges can be loaded into the dispenser by passing the one end of the roll into the container and over said locating member until the opposite end of the roll clears the free edge of the flange opposite said locating member whereupon the roll can be shifted within the dispenser and positioned upon said flanges between the said locating member and the opposite end of the said dispenser.

5. A dispenser adapted for dispensing a roll of sheet material comprising a front wall, end walls, flanges extending inwardly from the end walls and adapted to support the said roll adjacent its opposite ends, the flanges and lower edge of the front wall defining an opening through which said roll can be loaded into said dispenser, said flanges being spaced from the front wall to permit the passage of the free end of the sheet between the flanges and the said front wall, a locating member positioned immediately above one of said flanges and between the inner edge of said flange and the adjacent end wall, said locating member extending only a portion of the distance between its adjacent flange and the top wall and being adapted to cooperate with the lower portion of an end of said roll for maintaining said roll upon said flanges, the distance between the end wall adjacent the said locating member and the inner edge of the remote flange being greater than the distance between the inner edges of said flanges whereby a roll having a greater length than the distance between the inner edges of said flanges can be loaded into the dispenser by passing the one end of the roll into the container and over said locating member until the opposite end of the roll clears the free edge of the flange opposite said locating member whereupon the roll can be shifted within the dispenser and positioned upon said flanges between the said locating member and the opposite end of the said dispenser.
